F. M. STEADMAN,
DEVICE FOR DETERMINING THE ACTINIC POWER OF LIGHT;
APPLICATION FILED DEC. 22, 1915, RENEWED DEC. 13, 1917.

1,274,464.

Patented Aug. 6, 1918.

UNITED STATES PATENT OFFICE.

FRANK M. STEADMAN, OF CARACAS, VENEZUELA.

DEVICE FOR DETERMINING THE ACTINIC POWER OF LIGHT.

1,274,464.

Specification of Letters Patent. Patented Aug. 6, 1918.

Substitute for application Serial No. 871,281, filed November 10, 1914. This application filed December 22, 1915, Serial No. 68,286. Renewed December 13, 1917. Serial No. 207,018.

To all whom it may concern:

Be it known that I, FRANK M. STEADMAN, a citizen of the United States, and a resident of Caracas, Venezuela, have invented a new and useful Improvement in Devices for Determining the Actinic Power of Light, of which the following is a specification, this application being a substitute for my prior application, Serial No. 871,281, filed Nov. 10, 1914.

My invention relates to improvements in devices for determining the actinic power of light, and it consists in the combinations, constructions, and arrangements herein described and claimed.

An object of my invention is to provide a device which may be used in connection with photography to determine the actinic power of the light which is reflected from objects that are designed to be photographed.

A further object of my invention is to provide a device of the type described, which is of relatively small size so that it may be easily transported in the pocket of the user, but by means of which the actinic power may be readily determined.

A further object of my invention is to provide a device of the type described for determining the actinic power of the light reflected from objects whose light cannot be conveniently measured directly, by measuring or determining the actinic power of a standard surface provided with a movable part having light and dark portions which may be moved so as to vary the amount of light which is reflected from the surface as a whole.

Other objects and advantages will appear in the following specification and the novel features of the device will be particularly pointed out in the appended claims.

My invention is illustrated in the accompanying drawing, forming part of this application, in which—

Figure 1 is a sectional view through the device.

Fig. 2 is a sectional view on the line 2—2 of Fig. 1.

Fig. 3 is a face view of a portion of the standard light reflecting surface or screen.

Fig. 4 is a face view of the inner portion containing the light openings.

Fig. 5 is a face view of a portion of the sensitive strip showing the discolorations produced by exposure.

In carrying out my invention I provide a receptacle having a back 1, a front portion 1^a which, as will be afterward explained, serves as a backing for a sensitized strip, 60 sides 1^b, and a rear 1^c, which is preferably semi-circular in shape, as shown in the drawing.

Arranged to cover this receptacle is a plate 2 which is provided with a laterally 65 extending portion having a front plate 3, and a partition 4 with transverse partitions 5 connecting the plate 3 with the partition 4 and dividing the extension into a series of compartments.

The plate 3 is provided with a series of openings. These openings I have shown at a, b, c, d, e, f, but it will be understood that a larger or less number of openings may be provided without departing from the spirit 75 of the invention. The opening a is of arbitrary size and is preferably square. The opening b is one-half the size of the opening a, but it will be noted that the length of the opening b is the same as that of the opening 80 a. Similarly the openings c, d, e, f are one-half of the area of the preceding opening in the order named, the lengths of these openings, however, being precisely the same. In the rear partition 4 is a series of openings, 85 which in the present instance are made in the form of stars but which might be made in any suitable shape. These openings I have designated as a', b', c', d', e', f'. They are situated in alignment with the centers 90 of their respective openings a, b, etc., in the opposite wall 3 and each pair of openings, such as a, a', is separated from the adjacent pair, such as b, b', by one of the partitions 5.

Hinged at 6 to the extension is a cover 7 95 which may be moved to cover the openings a, b, etc., or swung into the position shown in Fig. 2 to make an exposure in the manner hereinafter described. It will be observed from Fig. 1 that this cover 7 has an extension 7^x which projects beyond the device in order to provide a convenient thumb piece

for opening the cover. The cover is hinged as shown in Fig. 4 and is provided with a spring 8 for holding it normally in a closed position so as to shut out light from entering the openings *a*, *b*, etc. It will be observed that there is a slot or passageway 9 which is left between the partition 4 and the side 1^a, see Figs. 1 and 2, through which the strip 10 may be drawn, this strip 10 consisting preferably of a sensitized band of paper or other suitable material. It will be noted that the strip is carried in a roll on the interior of the receptacle and that it passes out at one side as shown in Fig. 1, the sensitized portion of the strip facing the openings *a'*, *b'*, etc.

In Figs. 1, 2 and 3 I have shown the standard surface. This consists of a frame 12 having upper and lower rollers 13 the axle of one of these rollers being provided with a thumb wheel 14 for turning it. Arranged on the rollers is an endless belt or sheet consisting of a white portion 15 and a black portion 16. At one side of the frame 12 I provide a series of legends indicating the various kinds of objects which may be photographed and whose actinic power may be determined.

In order to hold the frame 12 at a predetermined distance from the sensitive strip I provide the side members 18, whose ends may be slipped into openings in the frame 12 the opposite ends being retained by means of devices 19 which are provided with sockets to hold the ends of the side members 18.

From the foregoing description of the various parts of the device, the operation thereof may be readily understood.

Consider now Fig. 1; if one should place his eye at the opening indicated by the small opening *a'* and look toward the screen, he could just see that portion of the screen which is subtended by the lines *x* and *y* in Fig. 1 and *w* and *z* in Fig. 2. This is substantially the full surface of the screen, so that with the instrument pointed at the screen, no other direct light will be sent to the sensitized film except that of the screen itself. Of course, if the eye is placed at any of the other openings, the amount of surface which sends direct light is decreased because of the fact that the rectangular opening in front of the star is smaller. Thus in Fig. 1 the surface which sends its light directly to the opening *b'* through the opening *b* is that between the lines *t* and *v*.

Let us consider now the measurement of actinic power of the average objects or view whether the day be bright or cloudy or otherwise. The belt is turned so that the dividing line 20 between the white and black portions 15 and 16, respectively, is opposite the legend average views in Fig. 3. It will be apparent that one-half of the screen will

reflect more light than the other half, the amount of reflection being equivalent to the reflection from the average object or view.

The sensitized strip is placed in position in the interior of the receptacle and the plate 2 with its lateral extension is brought into the position shown in Fig. 2, one end of the plate 2 being snapped into engagement with the wall 1^c of the casing so as to hold the parts together. The cover 7 is now forced downwardly by means of the thumb and an exposure is made for any predetermined time. Let us assume that this time is eight seconds. The cover is now released so as to fly back over the openings *a*, *b*, etc., thereby shutting off the light.

The sensitive strip may now be pulled outwardly, the roll unwinding as the strip moves and after examination the portion of the strip which has been pulled outwardly may be torn off leaving enough, of course, to enable one to pull another portion of the strip out after a subsequent exposure.

The exposure will cause the sensitized strip 10 to be acted on by the light thereby producing the usual discolorations which are made when a sensitized paper is exposed to the light. These discolorations are shown in Fig. 5 at *a''*, *b''*, and *c''* being progressively fainter. If the day had been darker than only two of the discolorations, to wit: *a''* and *b''*, would have been seen, or if the day had been lighter, there might be other impressions. The dimmest appreciable impression is noted, and the number 100 which corresponds to the opening, corresponds to the discoloration or impression. In this case the number is 32, and, therefore, the actinic power of the object, which in this case is an average view, in the light which was coming to the object at that time, that is to say, (a bright light, a subdued light, or still less light) is 32. This being known, one may time his exposure for an actinic power of 32.

There must be, of course, a standard unit of actinic power and this standard unit I have chosen arbitrarily as that actinic energy which is produced through an opening of fixed size, as for instance the opening *a* in 115 64 seconds of time. In ranging the numbers 8, 16, 32, 64, etc., opposite the openings *a*, *b*, *c*, *d*, etc., I made an exposure of eight seconds and on examining the strip found that only one star or discoloration showed on the 120 strip. If one star shows on an exposure of eight seconds, which is one-eighth of 64, then the amount of light, energy or power which will make this impression or discoloration is eight. The actinic intensity which 125 will make an impression on the paper through the next opening *b* which is one-half the size of *a* will, therefore, be 16, the next one 32, the next one 64, and so on.

Right here I desire to call attention to the 130

fact that while the widths of these openings *a*, *b*, *c*, *d*, *e*, and *f*, are one-half of the preceding opening, the lengths of these openings are precisely the same. Keeping one of the rectilinear dimensions of the openings uniform in length and varying their area by varying their width only enables the following desirable result to be obtained. Many objects to be photographed present no well extended plain surface, the light of which can shine into the actinometer. A distant "bird's-eye" view, a view consisting of all green grass and trees, and a group of flowers, are three such objects. As before explained the white and black portions of the screen are moved so that the dividing line will coincide with the object to be photographed. It is only by employing rectilinear openings of uniform length and varying width that any proportion of black and white will be preserved throughout the series of openings. This is not true where the openings in the wall 3 are circular or of any other form than that disclosed.

25 Of course, any other standard might be used without departing from the principle of the invention. The thing to do is to assign to the first opening a definite value, and the others will follow as a matter of course.

30 Where an object is near at hand and may be measured directly without the use of the endless tape, I prefer to do so. Thus in photography the light on the face of the person may be measured by holding the casing containing the sensitive strip up to the cheek and making the eight-second exposure as already described and then determining the actinic power by noting the faintest discoloration on the strip and taking the number opposite it. The sensitive strip does not need to be held at any given distance from the object or surface, provided the angle at which the light comes, is not too great to fall outside of the object itself; that is to say, the same result will be accomplished if I hold the device containing the sensitive strip an inch away from the cheek or one and one-half or two inches, because the nearer the cheek is approached the less surface sends light to the strip, while the farther away the more surface, and, therefore, the action on the strip is the same. When, however, the device is held so far away that it also takes in adjacent parts, such as the background behind the face, then the true actinic power of the reflected light from the face itself alone, is not being measured, but only an average measurement of the face and the background.

50 A device of this kind, enables any one, whether skilled in photography or not, to determine very accurately the time of exposure and it does away with guess-work so common in this art, thereby insuring good results, and decreasing to a large extent the

possibility of failure due to over or under exposure.

I claim:

1. In a device for determining the actinic power of light, a casing, a sensitive surface disposed within the casing, a wall carried by said casing, said wall being spaced from said sensitized surface and having a series of rectangular openings, the major axes of the series being parallel and of uniform length and the areas of the openings diminishing progressively from one end of the series in simple proportion. 70
2. In a device for determining the actinic power of light, a casing, a sensitive surface disposed within said casing, a wall carried by said casing, said wall being spaced from said sensitized surface and having a series of rectangular openings, the major axes of the series being parallel and of uniform length and the areas of the openings diminishing progressively from one end of the series in simple proportion, a partition disposed between said sensitized surface and said wall, said partition being provided with a series of openings of uniform size and arranged to register with the centers of the respective openings in the series in the wall. 80
3. In a device for determining the actinic power of light, a casing, a sensitive surface disposed within said casing, a wall carried by said casing, said wall being spaced from said sensitized surface and having a series of rectangular openings, the major axes of the series being parallel and of uniform length and the areas of the openings diminishing progressively from one end of the series in simple proportion, a partition disposed between said sensitized surface and said wall, said partition being provided with a series of openings of uniform size and arranged to register with the centers of the respective openings in the series in the wall. 90
4. In a device for determining the actinic power of light, a casing, a sensitive surface disposed within said casing, a wall carried by said casing, said wall being spaced from said sensitized surface and having a series of rectangular openings, the major axes of the series being parallel and of uniform length and the areas of the openings diminishing progressively from one end of the series in simple proportion, a partition disposed between said sensitized surface and said wall, said partition being provided with a series of openings of uniform size and arranged to register with the centers of the respective openings in the series in the wall, and a series of transverse partitions extending between said first-mentioned partition and said wall, the space between any two of said transverse partitions serving to inclose an opening in the wall and its corresponding opening in the first-mentioned partition. 100
5. In a device for determining the actinic power of light, a casing, a sensitive strip disposed within said casing, an extension carried by said casing and having a partition and a wall, said partition being arranged to lie normally next to said sensitized strip and being provided with a series of openings of uniform size, the wall of the extension being provided with a series of openings corresponding in number to the first-mentioned series, the major axes of the openings in the wall being parallel and of a uniform length, and the areas of the openings in the wall diminishing progressively from one end of the series in simple ratio, and a series of transverse partitions between said 110
6. In a device for determining the actinic power of light, a casing, a sensitive strip disposed within said casing, an extension carried by said casing and having a partition and a wall, said partition being arranged to lie normally next to said sensitized strip and being provided with a series of openings of uniform size, the wall of the extension being provided with a series of openings corresponding in number to the first-mentioned series, the major axes of the openings in the wall being parallel and of a uniform length, and the areas of the openings in the wall diminishing progressively from one end of the series in simple ratio, and a series of transverse partitions between said 120
7. In a device for determining the actinic power of light, a casing, a sensitive strip disposed within said casing, an extension carried by said casing and having a partition and a wall, said partition being arranged to lie normally next to said sensitized strip and being provided with a series of openings of uniform size, the wall of the extension being provided with a series of openings corresponding in number to the first-mentioned series, the major axes of the openings in the wall being parallel and of a uniform length, and the areas of the openings in the wall diminishing progressively from one end of the series in simple ratio, and a series of transverse partitions between said 130

partition and said wall, the space between any two of said transverse partitions inclosing an opening in the partition and its corresponding opening in the wall.

5. In a device for determining the actinic power of light, a casing, a sensitive strip disposed within said casing, an extension carried by said casing and having a partition and a wall, said partition being arranged to lie normally next to said sensitized strip and being provided with a series of openings of uniform size, the wall being provided with a series of openings corresponding in number to the first-mentioned series, the major axes 10 of the openings in the wall being parallel and of a uniform length, and the areas of the openings in the wall diminishing progressively from one end of the series in simple ratio, a series of transverse partitions 15 between said first-mentioned partition and said wall, the space between any two of the said transverse partitions inclosing an opening in the first-mentioned partition, and its corresponding opening in the wall, and 20 a cover hinged to said casing for shutting off the light from or admitting light to all the openings simultaneously.

6. In a device for determining the actinic power of light, a casing, a sensitive strip disposed within said casing, an extension carried by said casing and having a partition and a wall, said partition being arranged to lie normally next to said sensitized strip and being provided with a series of 30 openings of uniform size, the wall being provided with a series of openings corresponding in number to the first-mentioned series, the major axes of the openings in the wall being parallel and of a uniform length, and the area of the openings in the wall diminishing progressively from one end of the series in simple ratio, a series of transverse partitions 35 between said first-mentioned partition and said wall, the space between any two of said transverse partitions inclosing an opening in the first-mentioned partition and its corresponding opening in the wall, a cover hinged to said casing for shutting off the light from or admitting light to all 40 the openings simultaneously, a backing plate, said sensitized strip being arranged to be held between said backing plate and said first-mentioned partition.

7. In a device for determining the actinic power of light, a casing, a sensitive strip disposed within said casing, an extension carried by said casing and having a partition and a wall, said partition being arranged to lie normally next to said sensitized 55 strip and being provided with a series of openings of uniform size, the wall being provided with a series of openings corresponding in number to the first-mentioned series, the major axes of the openings in the

wall being parallel and of a uniform length, 65 and the areas of the openings in the wall diminishing progressively from one end of the series in simple ratio, a series of transverse partitions between said first-mentioned partition and said wall, the space between 70 any two of said transverse partitions inclosing an opening in the first-mentioned partition and its corresponding opening in the wall, a cover hinged to said casing for shutting off the light from or admitting light 75 to all the openings simultaneously, a backing plate, said sensitized strip being arranged to be held between said backing plate and said first-mentioned partition, and a series of numerals corresponding with the 80 series of openings in the first-mentioned partition and disposed upon that side of the first-mentioned partition which faces the sensitized strip when the latter is in its normal position. 85

8. The combination with a casing, of a sensitized strip disposed within the casing, a partition and wall carried by said casing, transverse partitions extending between said 90 first-mentioned partition and said wall, said first-mentioned partition having a series of uniform openings and said wall having a series of corresponding rectangular openings, the major axes of the rectangular openings 95 being parallel and of uniform length and the areas of said last-named series of openings diminishing progressively from one end of the series, a standard light reflecting surface rigidly secured to said casing for reflecting light through the openings in the 100 wall, and a movable cover for shutting off the light coming to the outer openings from the light reflecting surface or permitting the entrance of light from the light reflecting surface. 105

9. The combination with a casing, of a sensitized strip disposed within the casing, a partition and wall carried by said casing, transverse partitions extending between said 110 first-mentioned partition and said wall, said first-mentioned partition having a series of uniform openings and said wall having a series of corresponding rectangular openings, the major axes of the rectangular openings 115 being parallel and of uniform length and the areas of said last-named series of openings diminishing progressively from one end of the series, a standard light reflecting surface rigidly secured to said casing for reflecting light through the openings in the wall, a movable cover for shutting off the light coming to the outer openings from the light reflecting surface or permitting the entrance of light from the light reflecting surface, and means for varying the amount 120 of light reflected from the light reflecting surface. 125

10. The combination with a casing, of a

- 65 sensitized strip disposed within the casing, a partition and a wall carried by said casing, transverse partitions extending between said first-mentioned partition and said wall, said 5 first-mentioned partition having a series of uniform openings and said wall having a series of corresponding rectangular openings, the major axes of the rectangular openings being parallel and of uniform length 10 and the areas of said last-named series of openings diminishing progressively from one end of the series, a standard light reflecting surface rigidly secured to said casing for reflecting light through the openings 15 in the outer wall, a movable cover for shutting off the light coming to the outer openings from the light reflecting surface or permitting the entrance of light from the light reflecting surface, means for varying the 20 amount of light reflected from the light reflecting surface, said last-named means comprising an endless belt having a dark portion and a light portion, and means for shifting the endless belt. 25 11. The combination with a casing, of a sensitized strip disposed within the casing, a partition and a wall carried by said casing, transverse partitions extending between said first-mentioned partition and said wall, said 30 first-mentioned partition having a series of uniform openings and said wall having a series of corresponding rectangular openings, the major axes of the rectangular openings being parallel and of uniform length 35 and the areas of said last-named series of openings diminishing progressively from one end of the series, a standard light reflecting surface rigidly secured to said casing for reflecting light through the openings in the 40 wall, a movable cover for shutting off the light coming to the outer openings from the light reflecting surface or permitting the entrance of light from the light reflecting surface, means for varying the amount of 45 light reflected from the light reflecting surface, said last-named means comprising an endless belt having a dark portion and a light portion, means for shifting the endless belt, a frame for said light reflecting portion, and indicating data on the edge of the frame for indicating the position of the line of division between the dark and light portions of the light reflecting surface for a desired amount of reflection of light. 50 12. In a device for determining the actinic power of light, a casing provided with a partition having a series of light openings of uniform size, a sensitive strip disposed within the casing, means for holding the 55 strip against one side of the partition adjacent to said openings, a wall carried by the casing and spaced apart from said partition, said wall having a series of rectilinear openings corresponding in number to the open- 60 ings in the partition, said rectilinear openings varying in size, and transverse partitions between said first-mentioned partition and said wall, said transverse partitions being disposed between adjacent openings. 65 13. In a device for determining the actinic power of light, a casing provided with a partition having a series of light openings of uniform size, a sensitive strip disposed within the casing, means for holding the strip against one side of the partition adjacent to said openings, a wall carried by the casing and spaced apart from said partition, said wall having a series of rectilinear openings corresponding in number to the openings in the partition, said rectilinear 70 openings being of uniform length and of proportionately decreasing width, and transverse partitions between said first-mentioned partition and said wall, said transverse partitions being disposed between adjacent 75 openings. 80 14. In a device for determining the actinic power of light, a casing provided with a partition having a series of light openings of uniform size, a sensitive strip disposed within the casing, means for holding the strip against one side of the partition adjacent to said openings, a wall carried by the casing and spaced apart from said partition, said wall having a series of rectilinear openings corresponding in number to the openings in the partition, said rectilinear 85 openings being of uniform length and varying in width successively and in simple ratio, and transverse partitions between said first-mentioned partition and said wall, said transverse partitions being disposed between adjacent 90 openings. 95 15. In a device for determining the actinic power of light, a receptacle, a sensitized strip disposed within said receptacle and adapted to be drawn therefrom, a plate having openings of uniform size, said plate being disposed in close proximity to the sensitive side of the strip, a second plate or wall 100 spaced from the first-mentioned plate and being provided with rectilinear openings corresponding in number and registering with the respective openings in the first-mentioned plate, and partitions between said 105 plate for preventing the light coming through one of said rectilinear openings from interfering with that coming through another. 110 16. In a device for determining the actinic power of light, a receptacle, a sensitized strip disposed within said receptacle and adapted to be drawn therefrom, a plate having openings of uniform size, said plate being disposed in close proximity to the sensitive side of the strip, a second plate or wall 115 spaced from the first-mentioned plate and being provided with rectilinear openings 120 corresponding in number to the openings in the partition, said rectilinear openings varying in size, and transverse partitions between said first-mentioned partition and said wall, said transverse partitions being disposed between adjacent openings. 125

corresponding in number and registering with the respective openings in the first-mentioned plate, partitions between said plate for preventing the light coming through one of said rectilinear openings from interfering with that coming through another, and a cover for simultaneously

shutting off the light coming to said rectilinear openings or for admitting light simultaneously to said openings.

FRANK M. STEADMAN.
